DESIGN FOR A MECHANICAL PENCIL OR SIMILAR ARTICLE

Garfield L. Beckstrom, Chicago, Ill., assignor to
Autopoint Company, Chicago, Ill., a corporation
of Illinois

Application January 24, 1944, Serial No. 112,313

Term of patent 14 years

(Cl. D74—24)

To all whom it may concern:

Be it known that I, Garfield L. Beckstrom, a citizen of the United States, residing at Chicago, in the county of Cook and State of Illinois, have invented a new, original, and ornamental Design for Mechanical Pencil or Similar Article, of which the following is a specification, reference being had to the accompanying drawing, forming a part thereof.

In the drawing:

Fig. 1 is a front elevation of a mechanical pencil or similar article embodying my invention.

Fig. 2 is a side elevation thereof.

Fig. 3 is a rear elevation thereof.

Fig. 4 is a top plan view thereof.

My design for a mechanical pencil, with clip attached thereto, both of the configuration as shown, is characterized by the areas of fine grooves placed cross-wise and longitudinally on specific parts of the pencil in a manner as shown.

I claim:

The ornamental design for a mechanical pencil or similar article, substantially as shown and described.

GARFIELD L. BECKSTROM.
